UNITED STATES PATENT OFFICE.

CHARLES W. NICHOLAS, OF TARENTUM, PENNSYLVANIA, ASSIGNOR TO WALTER P. MURPHY, OF CHICAGO, ILLINOIS.

COUPLER RELEASE RIGGING.

Application filed December 30, 1919. Serial No. 348,358.

To all whom it may concern:

Be it known that I, CHARLES W. NICHOLAS, a citizen of the United States of America, residing at Tarentum, in the county of Allegheny and State of Pennsylvania, have invented certain new and useful Improvements in Coupler Release Rigging, of which the following is a specification.

My invention relates to that general type of uncoupling device shown in the patent to James R. Carmer, 799,446, dated Sept 12th, 1915, and, like the Carmer device my improved release rigging may be operated by means of the hand or foot when a trainman is standing on the corner step of the platform without liability of being caught between the end sills of the car when taking slack, and, furthermore enabling the trainman to use his signaling-lantern, or hand during the operation of uncoupling and immediately after the uncoupling operation.

My improved rigging may be operated by hand at the center or at the end of the car end sill when occasion requires.

A further object in my invention is to increase the lifting power of this type of release rigging which increase of power is desirable in connection with the new standard type of coupler now in general use. I accomplish these objects without interfering with the service movements of the coupler; and with these and other objects in view my invention consists of parts and combination of parts, as will be hereinafter more fully set forth.

In the drawings:

Fig. 1. is a top plan view of a portion of the end structure of a car, with my improved rigging mounted thereon.

Fig. 2. is a front elevation of a portion of the end structure of a car with my improved rigging mounted thereon.

Fig. 3. is a side elevation of the double fulcrum bracket.

Fig. 4. is a front elevation of Figure 3.

Fig. 5. is a detail perspective view of the end of the pin lifting lever.

The reference numeral 1 designates a portion of the end structure of a car, 2 a coupler and 3 a coupler lock pin which are of standard construction.

The bracket for my improved rigging consists of a base plate 4 which is suitably secured to the end structure of the car and is provided with the fulcrum members 5, 6,

positioned in different horizontal planes, the fulcrum member 5, being longer than the fulcrum member 6. The fulcrum members are provided with reduced screw threaded portions 7, 8.

The shifting or hand lever 9, has its outer portion permanently sagged downwardly so that the foot or hand portion 10 is normally positioned below the plane of the under face of the car end structure, whereby danger of the foot or hand of the operator being caught between the end sills of the adjacent car is eliminated. The inner end of the shifting lever 9, is enlarged and provided with an opening through such enlargement through which the fulcrum 6 projects. The diameter of the opening in the inner end of the shifting lever 9 is greater than the diameter of the fulcrum 6 whereby the lever 9 is loosely mounted on the fulcrum 6 so that the lever will not become jammed on its fulcrum due to any service movements that may be required of the lever. For instance the lever may slide backward and forward on the fulcrum to accommodate the draft and buffing action of the coupler.

The pin lifting lever is provided at its inner end with a reduced portion 11 adapted to loosely slide within the eye of the lock pin 3, said reduced portion terminating in a hook 12 to prevent accidental disengagement of the lifting lever 13 from the lock pin 3. The pin lifting lever 13 is provided intermediate its ends with the enlargement through which an opening is formed, the fulcrum 5 projecting through said opening. The diameter of the opening in the lever 13 is greater than the diameter of the fulcrum 5, for the purpose described. Beyond the eye in the lever 13 said lever is deflected downwardly as at 14 said downwardly portion terminating in a substantially U-shaped protuberance extending to one side of the lever 13, and positioned, when operatively mounted on its fulcrum, under the shifting lever 9, said shifting lever 9 being supported against accidental downward movement by the said U-shaped protuberance. The levers are secured on their fulcrums by means of nuts 15 or other suitable device, said nuts being screwed on the reduced portions 7 and 8 of the fulcrums. The inner end of the pin lifting lever, 13 being connected to the lock pin 3 of the coupler and moves with the coupler in draft and buffing movements.

therefore the lever must be loosely mounted on its fulcrum 5, as above described to permit of such movement and at the same time prevent the lever being jammed on its fulcrum.

To operate the lock pin 3 the outer end of the shifting lever 9 is moved downwardly in a vertical plane by the hand or foot of the operator and as the lever 9 is seated in the U-shaped protuberance 15 of the lever 13 such downward movement of the shifting lever moves the pin lifting lever 13 on its pivot this causes the inner end thereof to be elevated thereby lifting lock pin 3 and positioning said pin and its coupler in lock set position.

Changes may be made in the details of construction without departing from the scope of the appended claims.

20. What I claim is:—

1. In a release rigging for car couplers comprising a plurality of fulcrums adapted to be connected to a car end structure, a pin lifting lever of the first order loosely mounted intermediate its ends on one of said fulcrums, and adapted to be loosely connected at its inner end to the lock pin of a coupler, and a shifting lever of the second order loosely mounted at its inner end on the other of said fulcrums and adapted to engage the outer end of the pin lifting lever.

2. In a release rigging for car couplers comprising a plurality of fulcrums adapted to be connected to the car end structure, a shifting lever of the second order loosely mounted at its inner end on one of said fulcrums for movement in a substantially vertical plane, a pin lifting lever of the first order loosely mounted intermediate its ends on the other of said fulcrums and adapted to be loosely connected at its inner end to the lock pin of the coupler and adapted at its outer end to loosely engage the shifting lever intermediate its ends.

45. 3. A release rigging for car couplers, comprising a plurality of fulcrums adapted to

be secured to the end structure of a car, a shifting lever of the second order loosely mounted on one of said fulcrums at its inner end and adapted to move in a substantially vertical plane, a pin lifting lever of the first order loosely mounted intermediate its ends on the other of said fulcrums, and adapted at its inner end to be loosely connected to the lock pin of the coupler, the outer end of the pin lifting lever beyond its fulcrum, sagging downwardly and loosely engaging the shifting lever intermediate its ends.

4. A release rigging for car couplers, comprising a plurality of fulcrums adapted to be secured to the end structure of a car, a shifting lever of the second order loosely mounted at its inner end on one of said fulcrums, and adapted to move in a substantially vertical plane, a pin lifting lever of the first order loosely mounted intermediate its ends on the other of said fulcrums and adapted at its inner end to be loosely connected with the lock pin of a coupler, the outer end of the pin lifting lever beyond its fulcrum sagging downwardly and terminating in a substantially U-shaped extension extending from one side of the lever and adapted to loosely engage the shifting lever intermediate its ends.

5. In a release rigging for car couplers including a pin lifting lever of the first order pivotally mounted to move in a vertical plane, and having a pivot opening intermediate its ends, one end of the lever being reduced in diameter terminating in a return bend and adapted to be slidably mounted in the eye of a lock pin of a coupler, the other end of the lever beyond the pivot opening being provided with a substantially U-shaped extension offset from one side of the lever, and an operating lever of the second order cooperatively mounted and functioning with said pin lever.

In testimony whereof I affix my signature.
CHARLES W. NICHOLAS.
